DESIGN FOR A MATCH BOOK CASE

Robert Thomas Sporman, Essex County, N. J.,
assignor to The J. E. Mergott Co., Newark, N. J.,
a corporation of Delaware

Application January 22, 1948, Serial No. 143,976

Term of patent 3½ years

(Cl. D48—28)

To all whom it may concern:

Be it known that I, Robert Thomas Sporman, a citizen of the United States of America, residing in the county of Essex and State of New Jersey, have invented a new, original, and ornamental Design for a Match Book Case, of which the following is a specification, reference being had to the accompanying drawings, forming a part thereof.

Fig. 1 is a top end view of the match book case showing my new design;

Fig. 2 is a front view of the match book case;

Fig. 3 is a side view of the match book case; and,

Fig. 4 is a back view of the match book case.

I claim:

The ornamental design for a match book case, substantially as shown.

ROBERT THOMAS SPORMAN.
